UNITED STATES PATENT OFFICE.

WILLIAM CHARLES SPROESSER, OF BLOOMFIELD, NEW JERSEY, ASSIGNOR TO WESTINGHOUSE LAMP COMPANY, A CORPORATION OF PENNSYLVANIA.

EVACUATION OF BULBS AND THE LIKE.

Application filed September 7, 1923. Serial No. 661,382.

This invention relates to the manufacture of evacuated devices and more particularly to the exhaustion of incandescent electric lamps and other vessels.

5 An object of my invention is to manufacture evacuated devices in a simple and economical manner, avoiding the necessity of expensive vacuum pumps and like machinery.

10 Another object of my invention is to provide means to obtain the desired degree of vacuum in incandescent electric lamps and other devices by the use of readily vaporizable material which exerts no appreciable 15 vapor pressure at ordinary room temperatures.

A further object of my invention is to provide means for the evacuation of bulbs and the like by flushing with the vapor of a 20 material which is solid and exerts no appreciable vapor pressure at ordinary room temperatures and the subsequent removal of the vapor by condensation.

A still further object of my invention is 25 to create the desired degree of vacuum in incandescent electric lamps and other receptacles, by displacing the gaseous matter within such articles by a condensable vapor which, under certain conditions, may have 30 no appreciable vapor pressure.

Other objects and advantages of the invention will become apparent upon reading the following description.

In order to obtain the requisite degree of 35 vacuum in incandescent electric lamps and other receptacles, it is necessary, according to processes in ordinary use, to employ expensive vacuum pumps and the exhaustion of such devices by such means is relatively 40 slow.

According to my invention, I make use of a method which is adapted to eliminate the use of rotary pumps in the exhaust operations and in fact may be extended to eliminate entirely the use of vacuum pumps of 45 any description. This method may be called a physico-chemical process and consists essentially in creating the required degree of exhaust by the alternate vaporization and 50 condensation of a volatile solid.

A preferred method of practicing my invention may be briefly described as follows.

The lamp, or other vessel to be evacuated, 55 is connected to a bulb or flask containing a quantity of a solid substance which is pref-

erably white in color and has no appreciable vapor pressure at ordinary room temperatures. Likewise, this vapor should be stable when heated to the desired temperature of exhaust, that is, to about 400° C. Its boiling point should be at about the same temperature or lower than that of the exhaust oven or, if using vacuum, it should have a vapor pressure approximating atmospheric at that temperature and its melting point should preferably, although not necessarily, be at a temperature higher than ordinary room temperatures.

The type of lamp or other vessel most suitable for evacuating according to my invention is that of the tipless tipped variety or that in which an exhaust tube is provided extending through the flare tube or stem of the lamp and also a tubulation or exhaust tube is provided at the opposite end of the lamp bulb. The lamp bulb or other vessel may then be connected to the bulb or flask containing the material used for creating the desired vacuum, by either one of the exhaust tubes, leaving the remaining exhaust tube open to the atmosphere or connected to an 70 evacuating system or vacuum pump.

The lamp bulb or other vessel and the bulb or flask containing the solid connected thereto, may then be heated to the usual temperature of exhaust, preferably in an oven, thereby causing the solid to vaporize at least in part and displace the air in both vessels so that the same are completely filled with the vaporized solid which will then 80 start to either escape from the free exhaust tube or be drawn into the evacuating system connected to said exhaust tube. At this point, the lamp or the like may be either tipped off at the free exhaust tube or that 85 one connected to the evacuating system or at least, temporarily sealed at that point.

The bulb or flask containing the solid material used for the exhausting purpose, is then either cooled or allowed to cool while 90 maintaining the lamp in its heated condition. This causes the vaporized solid in the bulb or flask to recondense and solidify thereby causing the vapor in the heated lamp to flow to the cooled flask and be there 95 recondensed leaving an excellent vacuum in both vessels. When the bulb or flask containing the solid has been cooled to cause the condensation of substantially all the vaporized material in the vessels, the lamp 100

may then be tipped off at the exhaust tube between it and the flask and withdrawn from the oven to allow it to cool. Then, if not already permanently tipped off at the other 5 exhaust tube, this may be done and it will be found that an excellent vacuum has been created therein.

It will be apparent that the use of a vacuum pump or other mechanical exhausting 10 means is unnecessary, but may be employed if desired to expedite the process. Although a vessel or lamp with two exhaust tubes is preferably employed, so that the vapor can be admitted at one tube and allowed to flow out of the other, yet my method is applicable to lamps or vessels having only one exhaust tube, as they may be repeatedly flushed and exhausted to eliminate substantially all the original air therein. That is, the vessel may be heated, exhausted and filled with the vapor of the 15 substance used, again exhausted and refilled with the vapor and the process repeated until a negligible and harmless amount of air 20 remains. The bulb or flask containing the substance used for the exhaust process may then be cooled, as heretofore, while maintaining the lamp or other vessel hot and a 25 good vacuum created in the lamp bulb in the same manner as heretofore described.

My invention will better be understood by the following more detailed description taken, in connection with the accompanying drawing, the single figure of which illustrates a preferred apparatus for practicing my invention, shown in side elevation, partly in section.

A conventional form of incandescent electric lamp 1 of the vacuum type is illustrated, 40 but it is obvious that my method of exhaust is applicable for the evacuation of any receptacle. The lamp 1 illustrated, is shown provided with a mount 2 supplied with an exhaust tube 3 connected to the interior of a bulb thereof at 4. In other words, the mount 45 2 is a tipless type of mount, in that the lamp may be evacuated thereby through an exhaust tube therein and the usual tip on the other end of the bulb avoided. For the purposes of my invention, however, it is preferable that another exhaust tube 5 be provided, although the same is not essential.

The exhaust tube 5 may be connected in any desired manner, for example, rubber tubing connector 6 to means such as a stop-cock 7 for sealing the same from the atmosphere or from an evacuated system or pump (not shown) to which said exhaust tube 5 may be connected to, through stop-cock 7.

The lamp 1 is connected by one of its exhaust tubes to a bulb or flask 8, containing a quantity of a vaporizable solid 9. In this instance, it is shown connected to exhaust tube 3, but it is immaterial which tube is

employed, provided the other one is connected to means for sealing the bulb from the atmosphere or from a vacuum pump or system connected thereto. The flask 8 may be connected to the exhaust tube 3 by fusing 70 the neck 10 thereof to said exhaust tube or by some connecting means 11, which is air tight and unaffected by a temperature of 400 or 500° C., such as may be employed during 75 the exhausting operation.

The characteristics of the solid 9 used in the exhaust operation are that, (1) it should preferably have no appreciable vapor pressure at ordinary room temperatures, (2) its vapor must be stable when heated to the desired temperature of exhaust, that is, to about 400° C. or not higher than 500° C., (3) its boiling point should be at about the same temperature as that of the exhaust oven, that is, about 400° C. or less, (4) its melting point should preferably be at a temperature considerably above ordinary room temperatures, although this is not as essential as its vaporization characteristics, (5) it should preferably be white in color, (6) it should be relatively inexpensive and (7) which should have no detrimental effect on the filament.

The following halide salts have properties which make them acceptable for use.

Compound.	Melting point °C.	Boiling point °C.
AlBr ₃	93	263 10
AlCl ₃	Sublimes.	183
Al ₂	185	360
SiBr ₃	94	280

An oven 12 is provided with an opening 13 through which the exhaust tube 5 passes and lower doors 14 through which the lamp 1 and the flask 8 may be inserted or removed. Heating means of any preferred form may be provided for said oven and as shown, may comprise resistance wire 15 heated from any desired source of electricity (not shown) to provide the desired temperature in the furnace. An electric fan 16 may be provided, if desired, for cooling the flask 8 after removing the same from the 11 furnace.

The operation of the apparatus heretofore described for practicing my invention may be as follows: The lamp 1 and its connected flask 8 containing a quantity of the solid 9 is enclosed and held in position in the oven 12 in any desired manner, as by means of exhaust tube 5 and the stop-cock 6 is left open to the atmosphere or to a vacuum pump or other evacuating system, as may be desired. The resistance wire 15 is energized from a suitable source of electricity (not shown) to cause the lamp 1 and the flask 8 to be heated to about 400° C., thereby sufficiently baking out the lamp and vaporizing 11

material 9 to drive out the residual air in both the flask 8 and the lamp 1. When such has been accomplished, the furnace 12 may either be raised to the position 12' as shown by skeleton lines or the lamp and its connected flask so lowered that the flask emerges from the bottom of the furnace through the doors 14 and is allowed to cool or be cooled by any preferred means, as for example, the electric fan 16. As the flask 8 cools, the vapor therein condenses to its original solid form, thereby producing a partial vacuum and causing the vapor in the lamp 1 to flow back to the flask 8 through the exhaust tube 3 and neck 10.

When the flask 8 has been cooled to its original room temperature, all vapor in both the lamp 1 and flask 8 will be recondensed in the flask 8, thereby producing a good vacuum in both of said vessels. The lamp may then be tipped off as usual at the exhaust tube 3 and if not already permanently sealed at the exhaust tube 5, this may then be done to produce a lamp of the vacuum type, with a very high degree of vacuum therein.

It should be noted that aluminum bromide or the other halide salts mentioned are candle power maintenance materials, that is, when deposited on the bulb in thin layers they prevent to a large degree, blackening of the bulb by the deposition of vaporized filamentary material. Therefore, should traces of the halide salts remain in the bulb they will have no detrimental effect on the filament but rather will exert a beneficial effect.

Although I have described a preferred means of practicing my invention, illustrating preferred apparatus, it is to be understood that lamps or other vessels comprising only one, as well as two exhaust tubes, may be exhausted as described without departing from the spirit and scope of my invention, as it will be readily appreciated that the air in such lamps or the like may be removed by alternately evacuating the lamp and flushing with the vapor of the solid used until the air is eliminated

therein to any desired degree, after which the vapor may be recondensed in the vessel supplying the same as heretofore described. The use of a vacuum pump or other mechanical exhaust means is unnecessary with apparatus such as illustrated in the drawing, when exhausting lamps or the like provided with two exhaust tubes. However, when exhausting lamps or other vessels provided with only one exhaust tube, it is desirable to have some means for preliminarily exhausting the same, in connection with the flushing thereof with the desired vaporized material.

What is claimed is:

1. A material for the evacuation of a gas-tight enclosure, by displacement of the air therein comprising a vaporizable halide salt having no appreciable vapor pressure at room temperature and capable on condensation of leaving a first class vacuum in said enclosure.

2. A material for the evacuation of a gas-tight enclosure containing an incandescent filament, comprising a vaporizable halide salt capable on vaporization of displacing the air within said enclosure and on condensation of creating a first class vacuum therein, said material exerting no harmful effects on said incandescent filament.

3. A material for the evacuation of a gas-tight envelope, by displacement of the air therein, comprising aluminum bromide, said material on condensation leaving a first class vacuum within the envelope.

4. A material for the evacuation of incandescent electric lamps comprising a halide salt capable on vaporization of displacing the air within the lamp and on condensation of leaving a first class vacuum in the lamp, said material exerting no harmful effects on the filament and assisting by condensation on the envelope, of maintaining the candle power of the lamp.

In testimony whereof, I have hereunto subscribed my name this 6th day of September, 1923.

WILLIAM CHARLES SPROESSER.
